Primary Examiner — Carla Jobe Wright(74) *Attorney, Agent, or Firm* — Cheng-Ju Chiang(57) **CLAIM**

The ornamental design for a mobile phone leather sheath, as shown and described.

DESCRIPTION

FIG. 1 is a front, bottom and right perspective view of a mobile phone leather sheath showing our new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof, the bottom view being a mirror image of FIG. 6.

The dot-dash broken lines in FIG. 3 represent boundaries of the claimed design. The dash-dot broken lines depict environmental subject matter that forms no part of the claimed design. The broken lines form no part of the claimed design.
